(57) **CLAIM**

The ornamental design for a pendant, as shown and described.

DESCRIPTION

FIG. 1 is a front-bottom perspective view of a pendant according to the present invention.

FIG. 2 is a rear-top perspective view of the pendant.

FIG. 3 is a front elevational view of the pendant; and, FIG. 4 is a rear elevational view of the pendant.

The dashed broken lines depict portions of the pendant that do not form part of the claimed design. The dash-dot broken lines define the bounds of the claimed design and form no part thereof.
